UNITED STATES PATENT OFFICE.

KARL ROSS, OF LOS ANGELES, CALIFORNIA.

CHECK PROTECTOR.

Application filed November 20, 1922, Serial No. 602,166. Renewed May 25, 1925.

To all whom it may concern:

Be it known that I, KARL Ross, a former subject of the Czar of Russia (having declared his intention of becoming a citizen of the United States), residing at Los Angeles, in the county of Los Angeles and State of California, have invented a new and useful Check Protector, of which the following is a specification.

This invention relates to devices of the character employed in stamping on checks the amount for which the check is made payable.

An object of this invention is to provide a check protector comparatively small and compact in construction so that, if desired, it may be readily carried in the pocket.

Another object is to provide for feeding the check different distances according to the length of the word that has been previously stamped thereon, thus enabling the words, designating the amount of the check, to closely follow one another.

Another object is to effect the foregoing by a novel construction.

Another object is to provide for ready insertion of the check in the device.

Other objects and advantages will appear hereinafter.

The accompanying drawings illustrate the invention:

Figure 1 is a perspective view of a check protector constructed in accordance with the provisions of this invention, the slide being in its retracted position.

Fig. 2 is a top plan view of the check protector shown in Figure 1.

Fig. 3 is an enlarged broken elevation from the line indicated by 3-3, Figure 2.

Fig. 4 is a fragmental detail on the line indicated by 4-4, Figure 2, the parts being shown in the positions they occupy when the slide is retracted.

Fig. 5 is a sectional detail similar to Figure 4 with the parts in the positions they occupy when the slide is moved inwardly to stopped position.

Fig. 6 is a sectional detail of a fragment of the stamping belt, and the detent for engaging the elements thereof.

Fig. 7 is an enlarged bottom plan view of the check protector shown in the preceding views, the lower section and casing being omitted.

Fig. 8 is an enlarged broken detail, partly

in section, viewed from the line 8-8, Figure 7.

Fig. 9 is an enlarged top plan view with a portion of the casing broken away to disclose the stamping belt. 60

Fig. 10 is a top plan view of one of the stamping elements.

Fig. 11 is a bottom plan view of said stamping element.

Fig. 12 is a sectional detail on the line indicated by 12-12 Figure 2. 65

Fig. 13 is a sectional elevation on the line indicated by 13-13 Figure 9, the stamping belt being omitted.

Fig. 14 is an end elevation, partly in section on the line indicated by 14-14, Figure 13, the stamping belt being in place. 70

Fig. 15 is a top plan detail of the inking device.

Fig. 16 is an end elevation illustrating the two sections separated for insertion of the check, the operator's hand being indicated in dotted lines. 75

Fig. 17 is a view similar to Figure 16 showing the sections in closed position with 80 the scoring or perforating rollers engaging the check.

Fig. 18 is a detail of the idler scoring or perforating rollers and fragment of a check 85 on which they are operating.

Fig. 19 is a sectional view similar to Fig. 13, excepting that the inking device is different.

Fig. 20 is a sectional elevation on the line indicated by 20-20, Fig. 19. 90

There is provided a housing comprising upper and lower sections 21, 22, separated for the greater part of their length by a space indicated at 23, see Figs. 13 and 16. One end of the housing is semicircular, as indicated at 24 and constitutes a spring member to yieldingly hold the sections toward one another. The sections 21, 22 are confined within a casing 241 having a slot-like opening 242 in one edge. Slidably engaging the section 22 is a slide 25 which is normally held retracted, that is, in position projecting considerably beyond the edge of the section 22, by coil springs 26 that surround studs 27 fixed to the outer edge wall of the slide 25. The springs 26 are inserted in tubular guides 28 secured to the section 22. 100

The slide 25 is provided in its under face with a transversely extending rack 29 which engages a spur gear 30 loosely mounted on 110

a shaft 31 that is journaled in bearings 32, 33 carried by the section 21, see Fig. 7. One end portion 34 of the gear 30 constitutes one member of a ratchet clutch, the other member of said clutch being indicated at 35. Between the gear 30 and bearing 32 is a coil spring 36 which holds the clutch member 34 toward the clutch member 35. The clutch member 35 is integral with one end of a check-feeding roller 37 which is loose on the shaft 31. The teeth of the clutch members 34, 35 are formed so that when the slide 25 is moved inwardly the roller 37 does not rotate, but the clutch effects rotation of said roller when the slide is retracted by expansion of the springs 36.

Mounted in the section 21 is a guide comprising a plate 38 and endless rails 381 spaced from the side margins of the plate 20 to form ways 382 for an endless stamping belt 39. The stamping belt 39 comprises stamping elements 40, Figs. 10 and 11, preferably pivoted or hinged to one another as indicated at 41. These stamping elements 25 40 are provided with different words indicating different monetary values; for example, words representing numbers from one to twenty inclusive, hundred, thousand, dollars and cents. Of course, the words are 30 of varying lengths depending on the number of letters in them. The letters are preferably composed of fine lines slightly spaced as indicated at 42 in Figure 10, so that when the check is pressed against them 35 said letters will be cut or perforated into the check. Each of the stamping elements 40 is provided adjacent the end of the last letter of the word thereon with a pair of outstanding shoulders 43 along the longitudinal margins of said element. The reason 40 for this will appear hereinafter.

At one point the plate 38 is provided with a cam face 383 and each of the rails 381 is deflected as indicated at 44, see Fig. 13, 45 so that whichever stamping element registers with the cam faces 383 and rail portion 44 will be deflected below the level of the remaining elements of the stamping belt. In alinement transversely with the deflected 50 portions 44 of the rails are guides 45 in the form of rods, see Figs. 4, 5 and 9, said guides being secured at one end to the slide 25. Slidably mounted on the guides 45 is a slotted slide 46 having at one end a wedge 55 47. The opposite end of the slide 46, when the slide 25 is pressed inwardly, is adapted to be engaged by the shoulders 43 of that stamping element which at the time registers with the deflected portion 44 of the guide 60 rail. When the slide 46 is thus moved, the wedges 47 are driven between the upper face of the slide 25 and one end of a lever 48 which is fulcrumed at 49 on the slide 25. The other end of the lever 48 is held normally retracted by a spring 50 secured at

one end to the slide 25. The spring 50 is provided with a detent 51 adapted, when the lever 48 is operated as above mentioned, to selectively engage the teeth of a toothed portion 52 of the section 22. The slide 46, 70 when it comes to a stop, after operating the lever 48, constitutes an abutment which prevents further movement of the shoulder 43 and consequently limits inward movement of the slide. The notched portion 42 and 75 detent 51 are positioned some distance from the slide 46 so as to afford a second stop to limit inward motion of the slide in order that one end of the slide cannot be moved farther in than the other end thereof. 80

Fixed to the inner face of the outer edge wall of the slide 25 and extending through a slot 53 therein is a spring 54, see Figs. 7 and 8, and secured to said spring are members 55 having at their free ends wedges 56. 85 When the spring 54 is pressed inwardly it moves the members 55 and thus causes the wedges 56 to engage a shoulder 57 of the section 22, thus forcing the members 55 against cam faces 58 of rocking members 586 of the slide 25, thus to rock said members on a shaft or pivot 581 toward the member 21. 90

The shaft 581 is journaled in bearings 582 fixed to the plate 584 of the slide 25 95 and on said shaft are guide rollers 583 that operate between the slide plate 584 and rails 585 which constitute parts of the section 21. The rocking members 586 are provided with vertical slots 587 through which passes a 100 stop pin 588, the lower ends of the slots constituting abutments engaging the pin 588 to limit motion of the forward end of the slide away from the section 21.

Journaled in bearings 589 of the rocking 105 members 586 forwardly of the shaft 581, see Figs. 8 and 9, is a shaft 590 on which are mounted scoring rollers 59, 591. The roller 59 registers with the deflected portion 44 of the guide rails so that that portion of the check, indicated at *a*, which registers with the stamping element, that may be aligned with the rail portion 44, will receive pressure from the roller 59 as the slide 110 is moved inwardly, thus causing the letters 115 on said stamping element to perforate or be impressed in the check. The roller 591 scores or breaks the fibre of the signature space of the check.

Bearing upon the rear portions of the upper faces of the rocking members 586 are springs 68 secured to the slide 25. These springs tend to hold the front ends of the rocking members elevated so as to normally hold the rollers 59, 591, free of the check 125 that is in the device.

In Figs. 13 and 14, projecting from the upper face of the slide 25 is a slotted standard 60, the vertical slot 61 thereof being engaged by upper and lower shafts 62, 621. 130

The shafts are provided with spur gears 63 engaging racks 64 mounted on the inner face of the upper section 21. Thus movement of the slide 25 effects translation of the shafts 62, and during this movement the spur gears effect rotation of the shafts. The shafts 62, 621 are provided with inking rollers 65, 651, respectively, constructed of suitable material for absorbing ink that may be supplied manually or automatically by inking pads 66 mounted in cross members 67 supported by the racks 64, such cross members being at the forward end of the path of movement of each of the rollers 65 so that the inking rollers will receive ink from the pads at the forward extremity of motion of said rollers.

Now referring more particularly to Figures 19 and 20, the inking mechanism just described is omitted and in lieu thereof is the following construction. Brushes 69 are stationarily mounted above the upper run of the stamping belt in position to engage the stamping elements thereof as the belt moves.

Directly above the roller 37 is a roller 70 mounted on a shaft 71 which is carried by the upper section 21. The rollers 37, 70 are positioned near one edge of the housing, see Figures 16 and 17, and positioned near the other edge of said housing are idler rollers 72, 73 mounted on shafts 74, 75, respectively, the shaft 74 being carried by the section 21 and the shaft 75 by the section 22. Preferably the rollers 72, 73 are knurled or roughened so as to produce an impression upon the check when the check is passed therebetween. The corrugations or teeth of the roller 37 preferably interfit with the corrugations or teeth of the roller 70.

Mention has hereinbefore been made of the spring portion 24 tending to hold the sections 21, 22 toward one another with the rollers 72, 73 in contact and the rollers 37, 70 in contact. When inserting the check, it will be more practicable to first separate the sections 21, 22 as shown in Figures 13 and 16. I effect this by providing a wedge 76 registering with the space 23 and mounted on a spring 77 which is secured at one end to the upper section 21, said spring tending to normally hold the wedge 76 retracted as in Figure 17. When it is desired to separate the sections, the operator will press upon the spring 77 with his finger, somewhat as indicated in Figure 16, thus inserting the wedge between the sections 21, 22.

It may be desirable, especially when carrying the check protector in the pocket, to hold the slide 25 in its innermost position so as to make the protector as compact as possible. For this purpose, there is provided an angular slotted catch 78, the rivet 79 by which the catch is secured in place extending through the slot 80 in said catch. When the

catch is moved in one direction it throws the upper end, constituting a stop 81, see Figures 3 and 7, into the path of movement of the shoulder 82 on the slide 25. Thus, when the slide is moved to its innermost position and then the catch 78 shifted, as just explained, the slide will be held against retraction. When it is desired to release the slide the catch 78 will be shifted in the opposite direction to release the shoulder 82 from the stop 81.

Journalized transversely in the plate 38 is a shaft 83 provided on its projecting outer end with an operating knob 84, see Figs. 1, 9, 13, 19 and 20. To the shaft 83 are fixed a series of toothed wheels or sprockets 85, 86. The sprockets 85 are adapted to engage end slots 87 in the stamping elements 40 and the sprocket 86 is adapted to engage intermediate slots 88 in said stamping elements. Thus when the knob 84 is turned it causes the stamping belt to be operated so as to shift the desired stamping element into proper position for stamping upon the check.

The shaft 83 also carries a sprocket wheel 89, the teeth of which are adapted to engage holes 90 in an endless indicating belt 91 provided with numerals, as indicated at 92 in Figure 1 of the drawings. The relative positions of the stamping elements and the endless belt 91 are such that, when any one of the numerals 92 registers with a pointer 93 projecting from one edge of the opening 242, the stamping element having the corresponding number expressed by a word or words will be in registration with the track portion 44 ready for the stamping operation. The belt 91 passes around idler pulleys 94 rotatably mounted at the opposite ends of the slot 242.

In order that the operator may know when any particular stamping element is in exact position for the stamping operation and to releasably hold said element in such position, there is preferably secured to the plate portion 383 a spring detent 95 adapted to click into the slots 88 of the stamping elements as said elements are successively brought into position to register said slots with said detent. The edges of the slot 88 are beveled sufficient so that rotation of the stamping belt can be effected by turning the knob 84 to compress the detent 95 into a slot 96 in the face of the plate portion 383, see Figure 13.

The check protector described above operates as follows: The operator grasps the check protector in the hand somewhat after the manner indicated in Figure 16, producing pressure upon the spring 77 so as to insert the wedge 76 between the sections 21, 22. He then inserts the check in the space between said sections 21, 22 and forces said check along between the idler rollers 72, 73 through the slot 80 in said catch. When the

until said check is in correct position for having the amount for which it is payable stamped in the proper place thereon. Having manipulated the knob 84 to move the 5 stamping element having the desired word thereon into registration with an opening 97 in the upper section 21, said opening being adjacent the rail portion 44, the operator will grasp the device somewhat after the 10 manner disclosed in Figure 17 and will produce pressure upon the spring 54. This, as has hereinbefore been described, rocks the members 586 of the slide so as to bring the rollers 59, 591 to bear upon the check. The 15 operator increases the pressure upon the slide sufficiently to move the slide inwardly until the abutments 46 engage the shoulders 43 of the stamping element that is aligned with the opening 97. As the slide moves inwardly 20 the rollers 59, 591 perforate or break the fiber of the paper of the check, the roller 59 pressing the check against the letters of the stamping element and the roller 591 scoring the signature place on the check so as to 25 make it impossible to alter the signature without detection.

When the slide has thus come to a stop, the operator will reduce the pressure upon the slide so as to permit the springs 26 to retract said slide and the parts mounted thereon. This retractive movement of the slide effects feeding of the check only the distance corresponding to the length of the word that has been stamped, as hereinbefore explained. 30 If another word is to be stamped upon the check, the operator will manipulate the knob 84 to properly register the stamping element having thereon the desired word and he will then effect the foregoing described operations as before so as to stamp said word upon 35 the check. These operations will be continued until the full amount of the check has been stamped thereon. The check will then be withdrawn from the protector and, if desired, to facilitate this operation the wedge 40 76 may again be thrust between the elements 21, 22.

I claim:

1. In a check protector, the combination of 45 a housing comprising spaced sections, a stamping belt rotatably mounted in one of the sections, a slide shiftably mounted in the other section, and a roller mounted on the slide and operable by movement of the slide to traverse a portion of the stamping belt.

2. In a check protector, the combination of 50 a housing, a stamping belt rotatably mounted in the housing, a slide shiftably mounted in the housing, and a roller mounted on the slide and operable by movement of the slide to traverse a portion of the stamping belt.

3. In a check protector, the combination 55 of a housing, a stamping belt rotatably

mounted in the housing, a slide shiftably mounted in the housing and having a rocking member, means on the slide to effect rocking of the rocking member, and a roller mounted on the rocking member and operable by movement of the slide to traverse a portion of the stamping belt.

4. In a check protector, the combination of a housing, a stamping belt rotatably mounted in the housing, a slide shiftably mounted in the housing and having a rocking member, means on the slide operable by pressure of the operator's hand to effect rocking of the rocking member, and a roller mounted on the rocking member and operable by movement of the slide to traverse a portion of the stamping belt.

5. In a check protector, the combination of a housing, a stamping belt rotatably mounted in the housing, a slide shiftably mounted in the housing and having a rocking member, means on the slide including a wedge operable by pressure of the operator's hand to effect rocking of the rocking member, and a roller mounted on the rocking member and operable by movement of the slide to traverse a portion of the stamping belt.

6. In a check protector, the combination of a housing, a stamping belt rotatably mounted in the housing, a slide shiftably mounted in the housing, a roller mounted on the slide and operable by inward movement of the slide to traverse a portion of the belt, a shaft mounted on the housing, a check-feeding roller on said shaft, means yieldingly holding the slide retracted, and means operable by the slide during its retractive motion to effect rotation of the check-feeding roller, said means being inoperative by the slide during inward movement thereof.

7. In a check protector, the combination of a housing, a stamping belt rotatably mounted in the housing and comprising a plurality of stamping elements, there being different words on the stamping elements, shoulders at the ends of the words on the stamping elements, a slide shiftably mounted in the housing, an abutment on the slide, means to operate the belt to align any one of the shoulders with the abutment, a roller mounted on the slide and operable by movement of the slide to traverse the stamping element aligned with the abutment, the abutment being moved into engagement with the shoulder by inward movement of the slide, means to retract the slide, and means operable by the slide during its retractive motion to effect feeding of a check across the stamping belt, said means being inoperative by the slide during inward movement thereof.

8. In a check protector, the combination of a housing, a stamping belt rotatably

- mounted in the housing and comprising a plurality of stamping elements, there being different words on the stamping elements, a slide shiftably mounted in the housing, co-
5 operating means on the stamping elements and slide to limit inward movement of the slide to distances corresponding to the lengths of the words on the stamping elements, a roller mounted on the slide and operable by movement of the slide to traverse a portion of the stamping belt, and means operable by the slide during its outward motion to effect feeding of the check across the stamping belt, said means being inoperative by the slide during inward movement thereof.
9. In a check protector, the combination of a housing comprising sections yieldingly held toward each other, rollers mounted on
20 the adjacent faces of the sections, means operable to move the sections away from each other to permit the insertion of a check between the rollers, and means in the housing operable to stamp the check.
- 25 10. In a check protector, the combination of a housing comprising sections yieldingly held toward each other, a stamping element mounted in the housing, a shiftably mounted slide, a roller on the slide operating to traverse the stamping element when the slide is moved, and means operable to move the sections away from each other to permit the insertion of a check between the stamping element and roller.
- 30 11. In a check protector, the combination of a housing comprising sections yieldingly held toward each other, a stamping element mounted in the housing, a shiftably mounted slide having a rocking member, a roller on the slide, means operable to rock the rocking member to move the roller toward the stamping element, said roller traversing the stamping element when the slide is moved, rollers mounted on the adjacent
35 faces of the sections, and means operable to move the sections away from each other to permit the insertion of a check between the last named rollers.
12. In a check protector, the combination of a housing, a stamping belt having a plurality of stamping elements and rotatably mounted in the housing, each of said stamping elements having a slot, a spring detent mounted in the housing in the path of travel of the slots, operating means for the belt, and means to press a check against the stamping belt.
13. In a check protector, the combination of a housing, a stamping belt having a plurality of stamping elements and rotatably mounted in the housing, each of said stamping elements having a slot, a rotatably mounted shaft, a toothed wheel on the shaft to engage the slots successively to move the belt, and means to press a check against the stamping belt.
14. In a check protector, the combination of a housing, a stamping belt having a plurality of stamping elements and rotatably mounted in the housing, the stamping elements having thereon words of different lengths, shoulders on the elements at the ends of the words, a slide shiftably mounted in the housing, a member shiftably mounted on the slide and having a wedge at one end and forming an abutment at its other end to engage the shoulder of one of the stamping elements when the slide is moved inward, a lever to receive the thrust of the wedge, a spring tending to hold the lever against the wedge to retract said wedge, a toothed portion for the housing, a detent on the spring to engage the toothed portion when the lever is operated by the wedge, and a roller carried by the slide and adapted to traverse any one of the stamping elements according as the belt is moved to position to register the stamping elements with said roller.

Signed at Los Angeles, California, this 13th day of November, 1922.

KARL ROSS.
